UNITED STATES PATENT OFFICE.

NELSON E. TOUSLEY, OF BELMONT, AND ALLISON H. WHORF, OF WATERTOWN,
MASSACHUSETTS, ASSIGNORS TO HOOD RUBBER COMPANY, OF WATER-
TOWN, MASSACHUSETTS, A CORPORATION OF MASSACHUSETTS.

DESIGN FOR A BOOT.

55,730.

Specification for Design.

Patented July 6, 1920.

Application filed April 15, 1920. Serial No. 374,236. Term of patent 14 years.

To all whom it may concern:

Be it known that we, NELSON E. TOUSLEY, of Belmont, and ALLISON H. WHORF, of Watertown, both of Massachusetts, and citizens of the United States, have invented a new, original, and ornamental Design for Boots, of which the following is a specification, reference being had to the accompanying drawing, forming a part thereof.

The figure is a side elevation of the boot showing our improved design.

We claim—

The ornamental design for a boot as shown.

NELSON E. TOUSLEY.
ALLISON H. WHORF.
